UNITED STATES PATENT OFFICE.

DAVID GAREY AND WILLIAM B. TISHLER, OF PROVIDENCE, RHODE ISLAND.

DESIGN FOR A COMBINED LAMP AND REFLECTOR.

Application filed October 27, 1927. Serial No. 23,913. Term of patent 7 years.

To all whom it may concern:

Be it known that we, DAVID GAREY and WILLIAM B. TISHLER, citizens of the United States, residing at Providence, in the county of Providence and State of Rhode Island, have invented a certain new, original, and ornamental Design for a Combined Lamp and Reflector, of which the following is a specification, reference being had to the accompanying drawings, forming part thereof.

The figure is a perspective view of a combined lamp and reflector adapted for use as a flood light and illustrating the form and arrangement of the ornamental indentations

provided in the reflecting surface thereof as well as the ornamental form and appearance of the light as a whole including the novel form of the socket portion extending rearwardly from the reflecting surface.

We claim:

The ornamental design for a combined lamp and reflector substantially as shown and described.

In testimony whereof we have affixed our signatures.

DAVID GAREY.
WILLIAM B. TISHLER.
